US0D1001560S

(12) **United States Design Patent** (10) **Patent No.:** **US D1,001,560 S**
 Smith et al. (45) **Date of Patent:** **** Oct. 17, 2023**

(54) **ASSEMBLY FOR SECURING DISPLAY**(71) Applicant: **All Plastic, Inc.**, Rancho Cordova, CA (US)(72) Inventors: **William Thomas Smith**, Fair Oaks, CA (US); **Cheryl Ann Smith**, Fair Oaks, CA (US)(73) Assignee: **ALL PLASTIC, INC.**, Rancho Cordova, CA (US)(**) Term: **15 Years**(21) Appl. No.: **29/840,617**(22) Filed: **May 31, 2022****Related U.S. Application Data**

(62) Division of application No. 29/664,598, filed on Sep. 26, 2018, now Pat. No. Des. 956,454.

(51) **LOC (14) Cl.** ..... **06-04**(52) **U.S. Cl.**USPC ..... **D6/682**(58) **Field of Classification Search**

CLAIM

We claim the ornamental design for an assembly for securing display, as shown and described.

DESCRIPTION

FIG. 1 is a perspective view of a portion of an assembly for securing display in accordance with a first variant of said Design, in which the displayed article is in a resting position; FIG. 2 is a front view of the portion of the assembly for securing display shown in FIG. 1, in which the displayed article is in the resting position; FIG. 3 is a front view of the portion of the assembly for securing display shown FIG. 1, in which the displayed article is in a raised position; FIG. 4 is a left side view of the portion of the assembly for securing display shown in FIG. 1, in which the displayed article is in the resting position; FIG. 5 is a left side view of the portion of the assembly for securing display shown in FIG. 1, in which the displayed article is in the raised position; FIG. 6 is a right side view of the portion of the assembly for securing display shown in FIG. 1, in which the displayed article is in the resting position; FIG. 7 is a right side view of the portion of the assembly for securing display shown in FIG. 1, in which the displayed article is in the raised position. FIG. 8 is a rear view of the portion of the assembly for securing display shown in FIG. 1, in which the displayed article is in the resting position; FIG. 9 is a rear view of the portion of the assembly for securing DISPLAY shown in FIG. 1, in which the displayed article is in the raised position; FIG. 10 is a top plan view of the portion of the assembly for securing display shown in FIG. 1; and, FIG. 11 is a bottom plan view of the portion of the assembly for securing display shown in FIG. 1. The broken lines in the drawings are included for the purpose of illustrating subject matter which forms no part of the claimed design. The assembly for securing display is shown in various drawings with a symbolic break in its length. The appearance of any portion of the article between the break lines forms no part of the claimed design. Broken away portions of the assembly for securing display are shown in various drawings by an irregular line indicating the boundary of the claimed design and forms no part of the claim.
